UNITED STATES PATENT OFFICE.

JOHN WILLIAM NASMITH, OF STOCKPORT, ENGLAND.

WIRE-STITCHING MACHINE.

1,267,892.

Specification of Letters Patent.

Patented May 28, 1918.

Application filed June 12, 1917. Serial No. 174,236.

To all whom it may concern:

Be it known that I, JOHN WILLIAM NASMITH, of Stockport, England, have invented certain new and useful Improvements in 5 Wire-Stitching Machines, of which the following is a specification.

This invention relates to the clenching mechanism in use on wire stitching machines for clenching the legs of the staples after 10 they have been driven through the material and more particularly to that kind of wire stitching machine known as a corner stitcher in which a wire staple is driven around the corner of a box of cardboard or other material. In such a machine the legs of the 15 staple, preparatory to clenching, should be at right angles to instead of parallel to each other as in the flat stitch. The more the legs of the staple have to be forced from the 20 parallel direction the more difficult it becomes to cause them to take the proper direction owing to the spring of the wire and the 25 more difficult it is to clench them correctly, as they tend to meet the clencher block directly at right angles and are more frequently crushed or bent the wrong way.

The object of my invention is to obviate these defects by providing a clencher so made that the legs in passing through the 30 material cannot meet the clencher block at right angles and such that the clenching block gradually alters its angle in the process of clenching and has a folding action on the legs of the staple.

35 In order that the invention may be clearly understood a sheet of drawings is appended in which—

Figures 1 to 4 illustrate the existing mechanism and its defects.

40 Fig. 5, illustrates my improved mechanism as it appears just as clenching is about to begin and,

Fig. 6 is a view similar to Fig. 5, illustrating the mechanism as it appears when 45 the clench is completed.

Fig. 7 illustrates alternative means for limiting the movement of the clenchers to their clenching position.

Fig. 8 is a front view of the plunger 50 shown by Figs. 5 and 6.

Fig. 9 is a section on line 9—9 of Fig. 8.

In Fig. 1 the staple legs 1, are shown in their theoretical position, but their natural tendency, due to the spring of the wire is to 55 take the direction shown by the dotted lines 2. The faces 3 of the ordinary clenching plunger 4 are formed at right angles to each

other as shown and are roughened so as to hold the end of the wire and force it around to the clenched position shown in Fig. 2 60 and it will be understood that the ram R which has driven the staple remains pressing on it until clenched. But it frequently happens that the staple legs are crushed as shown on the left of Fig. 3 or distorted as 65 on the right. If the plunger face does not hold the wire, the legs are clenched the wrong way as in Fig. 4. To obviate these defects loose clencher blocks have been used which have been hinged on the plunger and 70 each provided with a pin running in a shaped groove in the front plate which caused the faces, as they moved upward to 75 clamp, to move slightly toward the center. But the movement so obtainable is insufficient to obtain the desired result with certainty.

Fig. 5 shows the preferred embodiment of my invention with its parts in position when clenching is about to commence, the front 80 plate being removed. The plunger 5 is forced up and down or reciprocated in the usual way at the proper moment and slides in a relatively wide groove 6^a in the fixed guiding plate 6 and has formed on its back 85 a relatively narrow rib 7 Figs. 8 and 9 fitting in a narrower groove 6^b in the plate 6.

This narrow rib 7, projects somewhat beyond the broader main part of the plunger 5. As near the top and as near the longitudinal center of this narrow rib 7, as is possible without weakening the construction, two pins 8, are fixed, upon which are hinged at their inner ends the loose clencher blocks 9, said pins being at opposite sides of and 90 equidistant from said longitudinal center 9.

When the plunger 5 is in its lowest position the upper or clenching faces of the two blocks are compelled, as described below, to assume approximately a horizontal 100 line so that when the legs are not at right angles to each other, as is always the case, but tending toward the parallel as shown by the dotted lines 11, they will strike the clenching faces of the blocks at an angle 105 which causes them to bend in the desired direction. Formed on each clencher block is a projection 12 which rests on a ledge 13 formed on the plate 6, while the vertical face of each block rests against the inner face of 110 the wider groove 6^a in the plate 6, the ledges being transverse to the longitudinally extending guiding means formed by said groove. The object of these projections 12

and ledges 13 is two fold; when the plunger rises to clench, carrying with it the inner ends of the blocks 9 the ledges 13 act as supports for the projection 12 of the blocks 9 to pivot and slide on, so that the transition of the clenching faces from the horizontal position to the angular position Fig. 6 is gradual, the clenching faces swinging approximately as radii on the points of the projections 12 as centers.

When the plunger again descends the ledges and projections compel the faces to assume the horizontal position. By suitably forming the blocks, the two upper clenching faces, instead of forming a horizontal line, may be caused to dip slightly below it at the center and to assume a wide V shape. The top end of the broader main part of the plunger 5, shown by Figs. 5 and 6, is made to form a right-angled shoulder 14, constituting a stop and the lower part of each clencher block has a flattened face 15 parallel to the clenching face. The object of the stop 14 and faces 15 is to insure that when the plunger has risen, the faces 15 will abut on the stop 14 and prevent the clenching faces of the blocks 9 from assuming toward one another an angle less than a right angle, and also to insure that this right angle shall be bisected by the center line of the plunger, the clenching faces being therefore properly centralized. When the staple has been driven the plunger 5 is forced upward and the blocks gradually assume the position shown in Fig. 6, with their clenching faces at right angles to each other. Other means to limit the fall or swinging movement of the blocks to their clenching position may be used in place of the stop 14 and the faces 15, as for instance, a central pin or stop 14^a on the rib 7, Fig. 7, and corresponding notches or recessed faces in each block 9.

In the manner described, the legs of the staples are first given a proper direction as they emerge inside the box into which they are driven, and are then folded gradually over with certainty and properly clenched without crushing or distortion.

Claims:

- 50 1. In a clenching apparatus for corner stitchers, the combination of a pair of loose clencher blocks having clenching faces, and block-operating mechanism having means for maintaining said clenching faces approximately in alinement with each other at the commencement of the clenching operation and for causing said faces to gradually assume a position at right angles with each other as the clenching operation proceeds.
- 60 2. In a clenching apparatus for corner stitchers, the combination of a pair of loose clencher blocks having clenching faces, and block-operating mechanism having means

for maintaining said clenching faces approximately in alinement with each other at 65 the commencement of the clenching operation and for causing said faces to gradually assume a position at right angles with each other as the clenching operation proceeds, said mechanism including a reciprocating plunger to which the clencher blocks are pivoted at points close to the upper end and the center line of said plunger, and at opposite sides of and equidistant from said center line.

3. A clenching apparatus embodying the combination specified by claim 1, said mechanism including a reciprocating plunger to which the clencher blocks are pivoted, and means for supporting the outer ends of the 80 clencher blocks, during the clenching operation, said means having provisions for positively compelling a gradual change of the clenching faces from their alined position to their angular position when the plunger rises, and for positively compelling a gradual change of the said faces from their angular position to their alined position when the plunger descends.

4. A clenching apparatus embodying the 90 combination specified by claim 1, said mechanism including a reciprocating plunger to which the clencher blocks are pivoted, and means for limiting the swinging movement of the blocks to their clenching position to 95 prevent their clenching faces assuming less than a right angle relatively to each other, and to maintain said faces properly centralized.

5. In a clenching apparatus for wire 100 stitchers, the combination of a fixed guiding plate having longitudinally extending guiding means and transverse ledges, a reciprocating plunger guided by said guiding means, and clencher blocks pivoted to one 105 end portion of said plunger and provided with clenching faces, and with projections coöperating with said ledges.

6. In a clenching apparatus for wire 110 stitchers, the combination of a fixed guiding plate having longitudinally extending guiding means and transverse ledges, a reciprocating plunger guided by said guiding means, and clencher blocks pivoted to one 115 end portion of said plunger and provided with clenching faces, and with projections coöperating with said ledges, the plunger being provided with a stop, and the clencher blocks with faces coöperating with said stop.

In testimony whereof I have affixed my 120 signature in presence of two witnesses.

JOHN WILLIAM NASMITH.
